UNITED STATES PATENT OFFICE

2,567,881

CATCH CONSTRUCTION FOR CASES

Clayton Fyfe, Elgin, Ill., assignor to Illinois Watch
Case Co., a corporation of Illinois

Application August 15, 1947, Serial No. 768,748

7 Claims. (Cl. 292—128)

1

This invention relates to a catch construction for holding a closure member latched to a body member, and relates particularly to a catch construction including a catch member and a spring means.

In certain objects having a body member and a closure member it is customary to provide a spring urged catch member engageable with a latch member to hold the closure member in closed position against the body member. This construction is used on compacts, cigarette cases and other containers. As these containers are frequently small, the parts that comprise the catch construction will be very tiny. This adds to the difficulty of assembling the parts and making them strong enough to withstand the ordinary wear of everyday use. It also adds to the cost of the objects as a considerable amount of labor is involved in assembling the catch parts. Frequently the catch member was mounted on a spring and attached thereto and the spring was attached to a portion of the container by a small rivet or the like. The assembly of these various parts involved considerable labor. The present invention is concerned with an improved catch construction wherein a catch member is removably associated with a spring means being arranged to bear against a portion of the container to urge the catch member to a closed position and also to hold the parts of the catch in their assembled relationship. With this construction, the catch is simple to assemble and requires no permanent fastening devices such as rivets or the like.

One of the features of the present invention is the provision of an improved catch construction for holding a closure member latched to a body member; another feature of this invention is the provision of such a catch construction including a spring means with a catch member removably associated therewith and with the spring serving to hold the catch member and spring in assembled relationship and also to urge the catch member toward its closed position; a further feature of this invention is the provision of such an assembly wherein the catch member is held in an opening in one portion of the container and is rockable about a section of the container adjacent the opening with the spring means serving to urge the catch member into engagement with a latch member, maintain the spring means in engagement with the catch member and retain the catch member in its opening; a still further feature of the invention is the provision of improved means for positively locking the spring

2

means and the catch member together so as to prevent their accidentally becoming disassembled. Other features and advantages of the invention will become apparent in the following description and claims when considered in conjunction with the embodiments shown in the accompanying drawings.

Of the drawings, Fig. 1 is a plan view of a cigarette case, or the like, in opened position and including a catch construction made according to the present invention; Fig. 2 is a side elevation of the cigarette case of Fig. 1; Fig. 3 is a fragmentary section, partially broken away, taken along line 3—3 of Fig. 4; Fig. 4 is a fragmentary section taken along line 4—4 of Fig. 6; Fig. 5 is an enlarged fragmentary end elevation showing the case in closed position and illustrating the outer portion of the catch construction; Fig. 6 is an enlarged fragmentary section through the closed cigarette case and showing the catch construction in section; Fig. 7 is a fragmentary plan view of a catch construction showing a second embodiment of the invention; Fig. 8 is a fragmentary elevation of the catch construction of Fig. 7; Fig. 9 is an enlarged fragmentary elevation showing the opening in the case through which the catch member is adapted to be inserted; Fig. 10 is a fragmentary enlarged section similar to Fig. 6 but illustrating the second embodiment of the invention; Fig. 11 is a perspective view of the catch member of the embodiment of the invention shown in Figs. 7 to 10, inclusive; Fig. 12 is a perspective view of a catch member similar to that illustrated in the embodiment shown in Figs. 1 to 6 inclusive but having a finger-engageable portion of a type different from that shown in said figures; Fig. 13 is a view similar to Figs. 6 to 10, but showing another embodiment of the invention; Fig. 14 is a fragmentary section taken along line 14—14 of Fig. 13; Fig. 15 is a fragmentary section taken along line 15—15 of Fig. 13; and Fig. 16 is a fragmentary section taken along line 16—16 of Fig. 13.

In the embodiment shown in Figs. 1 to 6, inclusive, the catch construction is applied to a cigarette case. This cigarette case comprises a body member or bottom 20 and a closure member or top 21 with the two members being hinged together by means of a hinge 22. The top is shown in closed position by dotted lines in Fig. 2. The bottom 20 and top 21 are urged toward open position by means of a coil spring 23 located around a hinge pin 24 and having one end 23a bearing against the inner surface of the bottom

20 and another end 23b bearing against the inner surface of the top 21.

The bottom 20 of the cigarette case is provided with a catch near its outer edge with the catch being adapted to engage a latch member 25 on the top 21 of the case. The latch member 25 is in the form of an inwardly directed lip which is made integral with the top 21 of the case.

The catch comprises a catch member 26 and a spring 27 removably associated together. The catch member 26 is insertable through a slot 20a provided in the bottom 20 of the cigarette case. This slot is located near the front edge of the bottom 20 and has a top portion 20b narrower than its bottom portion. The catch member 26 comprises a shank portion 26a adapted to be inserted through and held within the slot 20a, a catch portion 26b adapted to engage the lip 25 and a finger-engageable portion 26c adapted to be located on the outside of the case as shown in Fig. 6 and to be rockable about the section of the case adjacent the opening 20a.

The shank 26a of the catch member 26 is provided with a slot 26d therein having a narrow upper part 26e.

The spring 27 comprises a bow portion 27a having ends 27b and 27c curved to bear against the inner surface of the bottom 20 of the cigarette case. The spring 27 also includes a pair of spring projections 27d arranged in spaced-apart relationship and a central interlocking portion 27e located between the projections 27d. The interlocking portion 27e is in the form of a T so that the top 27f thereof is wider than the remainder of the interlocking portion. The projections 27d are adapted to bear against the back of the shank 26a of the catch member 26 as shown on Fig. 6. The interlocking portion 27e of the spring is adapted to be inserted through the slot 26d and moved upwardly to the narrow upper part 26e of the slot. The top 27f of the interlocking portion 27e will then bear against this narrow upper part to hold the spring 27 and catch member 26 in its assembled relationship. The projections 27d serve as bearing surfaces contacting the shank 26a, and in the locked position confine the shank between their surfaces 27d and the projections 27f; the interlocking portion 27e being held against the top of the slot 26e, with the surfaces 27d, 27e and 27f of the member 27 being held in contact by virtue of the moment exerted by the member 27 against the case 20 at the ends 27b of said member.

The spring 27 is initially made as a flat stamping. The ends 27b and 27c are then formed, as shown, and the spring projections 27d are bent upwardly. The interlocking portion 27e is bent slightly downwardly, as is shown in Fig. 6. In assembling the unit, the shank 26a of the catch member 26 is inserted through the slot 20a in the bottom 20 of the cigarette case and the catch member is arranged in the position it is to occupy in the finished catch. The interlocking portion 27e of the spring 27 is then inserted through the slot 26d and moved upwardly to the top of the slot. In this position the top 27f of the interlocking portion is retained behind the narrow upper part 26e of the slot 26d. As the ends 27b and 27c of the spring bear against the bottom 20 of the case, the tension in the spring serves to hold the parts in assembled relationship and to urge the catch portion 26b of the catch member 26 into engagement with the lip 25. The finger-engageable portion 26c of the catch member, being rockable about the portion of the case ad-

jacent the slot 20a, may be moved toward the case to force the catch portion 26b away from the lip 25 and against the pressure of the spring and thereby permit the coil spring 23 to force the case open. In the open position of the catch, ends 27b serve as stops to limit the extreme position of catch member 26 by contact with the slot 20a. The case may be closed by merely bringing the bottom 20 and top 21 of the case together. When this is done, the catch member 26 automatically engages the lip 25 as the top of the catch portion 26b is provided with a cam surface 26f which is engaged by the bottom of the lip 25 to force the catch member back against the urging of the spring 27.

In order to aid in rocking the catch member and to make this rocking action smoother in operation, the inner surface of the finger-engageable portion 26c of the catch member may be provided, if desired, with a hump 26g that is located adjacent the slot 20a. This hump is formed by making the finger-engageable portion 26c in two different planes, as is shown in Fig. 6. This hump, however, is not necessary and any other type of construction may, of course, be used such as by merely making the finger-engageable portion 26c longer than the shank 26a.

The spring 27 serves to urge the interlocking portion 27e of the spring to the top of the slot 26d in the catch member 26 and thus hold the spring and the catch member in assembled relationship. The catch member is made rockable by having the angle between the shank 26a and the finger-engageable portion 26c greater than the angle between the shank 26a and the adjacent portion of the bottom 20 of the case when the catch member is in closed position.

In the embodiment shown in Figs. 7 to 10, inclusive, the catch member 126 is provided with a shank 126a insertable through a slot 120a in the bottom 120 of the cigarette case, a catch portion 126b and a finger-engageable portion 126c. The lateral sides of the shank portion 126a are each provided with a slot 126j. A spring 127 is provided having a bow portion 127a, curved ends 127b and an interlocking portion 127e. The lateral sides of the interlocking portion 127e are provided with extensions 127h. These extensions are adapted to be bent around so as to lie within the slots 126j and with the ends of the extensions bearing against the shank 126a of the catch member 126 as shown in Fig. 7. This serves to hold the catch member 126 and spring 127 in assembled relationship. The operation of the catch construction is the same as that previously described for the embodiment shown in Figs. 1 to 6, inclusive. The spring 127 urges the catch portion 126b into engagement with the lip 125 on the top 121 of the case, as is shown in Fig. 10.

In Fig. 12 there is shown a catch member 226 having a shank portion 226a similar to the shank portion of the catch member shown in Figs. 1 to 6, inclusive. This shank portion 226a is provided with a slot 226d having a narrow top part 226e and a catch portion 226b. This catch member differs from that shown in Figs. 1 to 6, however, in that the finger-engageable portion 226c is constructed in a single plane, instead of being provided with a hump as is shown at 26g.

In the embodiment shown in Figs. 13 to 16, inclusive, the catch member 326 has the catch portion 326a thereof provided with an inclined relatively long slot 326d and a shorter slot 326e with the shorter slot 326e being arranged longitudinally of the catch portion 326a and the two slots

merging into each other as is best shown in Fig. 15. The two slots 326d and 326e are arranged so as to form an X with the result that the lower right corner and the upper left corner of the shorter slot 326e extends from the sides of the longer slot 326d, as viewed in Fig. 15.

The spring 327 is similar to that previously shown in Figs. 1 to 6 and is provided with a bow portion 327a and an interlocking portion 327e. The interlocking portion 327e is in the form of a T so that the top 327f thereof is wider than the remainder of the interlocking portion. The spring 327 is also provided with projections 327d that are adapted to bear against the back of the shank 326a of the catch member 326, as is shown in greater detail in Figs. 13 and 16.

In assembling the spring 327 and the catch member 326, the spring is turned relative to the catch member so that the wide portion 327f of the interlocking portion 327e of the spring may be inserted through the long inclined slot 326d. After this insertion, the spring may be turned back so that the interlocking portion 327e is held within the shorter slot 326e, as is best shown in Fig. 15. The pressure of the spring against the bottom of the case will then hold the spring and the catch member in assembled relationship. In this assembled relationship it is practically impossible to disassemble the spring and the catch member without the use of special tools. This construction is very useful as it prevents accidental disassembling of the catch such as would occur if the spring in the embodiment shown in Figs. 1 to 6 were depressed in the area adjacent its center section. It is to be understood, however, that during ordinary use, the embodiment shown in Figs. 1 to 6 will remain in its assembled relationship as shown in these figures.

Having described my invention as related to the embodiments shown in the accompanying drawings, it is my intention that the invention be not limited by any of the details of description unless otherwise specified, but rather be construed broadly within its spirit and scope as set out in the accompanying claims.

I claim:

1. A catch construction for holding a closure member latched to a body member, comprising: a catch member insertable through an opening in one of said members and including a finger-engageable portion adapted to be located on the outside of said one member and a catch portion adapted to be located on the inside of said one member, said catch member having said portions thereof rockable about the portion of said one member adjacent said opening; a latch member on the other member and engageable by said catch member; and spring means removably associated with said catch member and urging the catch member toward the latch member for engagement therewith, said spring means including a portion insertable through an opening provided in said catch member and removably retained therein.

2. A catch construction for holding a closure member latched to a body member, comprising: a catch member insertable through an opening in one of said members and including a finger-engageable portion adapted to be located on the outside of said one member and a catch portion adapted to be located on the inside of said one member, said catch member having said portions thereof rockable about the portion of said one member adjacent said opening; a latch member on the other member and engageable by said

catch member; and spring means removably associated with said catch portion and bearing against an inner surface of said one member for urging the catch portion toward the latch member for engagement therewith, said spring means including a portion insertable through an opening provided in said catch member and removably retained therein.

3. A catch construction for holding a closure member latched to a body member, comprising: a catch member insertable through an opening in one of said members and including a finger-engageable portion adapted to be located on the outside of said one member and a catch portion adapted to be located on the inside of said one member, said catch portion having an opening therein with the top part of said opening reduced, and said catch member being rockable about a part of said one member adjacent said opening therein; a latch member on the other side of said closure and body members and engageable by said catch portion; and spring means having a portion insertable through said opening in said catch portion and retained in said reduced part of the opening with said spring means bearing against the inner surface of said one member to urge the catch portion into engagement with the latch member, maintain the spring means in engagement with the catch portion, and retain the catch member in its opening.

4. A catch construction for holding a closure member latched to a body member, comprising: a catch member insertable through an opening in one of said members and including a finger-engageable portion adapted to be located on the outside of said one member and a catch portion adapted to be located on the inside of said one member with said portions being arranged at an acute angle with respect to each other, said catch portion having an opening therein with the top part of said opening reduced, and said catch member being rockable about a part of said one member adjacent said opening therein; a latch member on the other of said closure and body members and engageable by said catch portion; and spring means having a portion insertable through said opening in said catch portion and retained in said reduced part of the opening with said spring means bearing against the inner surface of said one member to urge the catch portion into engagement with the latch member, maintain the spring means in engagement with the catch portion, and maintain the catch member with said angle between said portion thereof against an edge of the opening in said one member.

5. A catch construction for holding a closure member latched to a body member, comprising: a catch member insertable through an opening in one of said members and including a finger-engageable portion adapted to be located on the outside of said one member and a catch portion adapted to be located on the inside of said one member with said portions being arranged at an acute angle with respect to each other, said catch member being rockable about a part of said one member adjacent said opening therein; a latch member on the other of said closure and body members and engageable by said catch portion; and spring means having a portion embracing a part of said catch portion and another portion bearing against the inner surface of said one member to urge the catch portion into engagement with the latch member and maintain the catch member with said angle

between said portion thereof against one edge of the opening in said one member.

6. A catch construction for holding a closure member latched to a body member, comprising: a catch member insertable through an opening in one of said members and including a finger-engageable portion adapted to be located on the outside of said one member and a catch portion adapted to be located on the inside of said one member, said catch member having said portions thereof rockable about the portion of said one member adjacent said opening; a latch member on the other member and engageable by said catch member; and spring means removably associated with said catch member and urging the catch member toward the latch member for engagement therewith, said spring means including a portion insertable through an inclined opening provided in said catch member and then being movable to a position where the longitudinal axes of the spring means and the catch member are substantially parallel, and said spring means including a portion adapted to abut against the catch member and hold the spring means and catch member in the thusly assembled relationship.

7. A catch construction for holding a closure member latched to a body member, comprising: a catch member insertable through an opening in one of said members and including a finger-engageable portion adapted to be located on the outside of said one member and a catch portion adapted to be located on the inside of said one member with said portions being arranged at an acute angle with respect to each other, said 35

5
